UNITED STATES PATENT OFFICE

CHARLES A. ROLFE, OF ADRIAN, MICHIGAN, ASSIGNOR, BY MESNE ASSIGNMENTS, TO
ROLFE ELECTRIC CO., OF ROCHESTER, NEW YORK, A CORPORATION OF NEW YORK.

THERMAL ELECTRICAL PROTECTOR.

1,005,475.

Specification of Letters Patent. Patented Oct. 10, 1911.

Application filed April 21, 1902. Serial No. 104,022.

To all whom it may concern:

Be it known that I, CHARLES A. ROLFE, a citizen of the United States, residing at Adrian, in the county of Lenawee and State of Michigan, have invented a certain new and useful Improvement in Thermal Electrical Protectors, of which the following is a full, clear, concise, and exact description, reference being had to the accompanying drawings, forming a part of this specification.

My invention relates to thermal protective devices for protecting low tension circuits such as telephone, fire alarm and the like, from the injurious effects of unduly strong currents such as emanate from electric light and power circuits.

Prominent objects of my present invention are to provide a simple, practical and inexpensive device of this kind, and to allow the delay incident to repairing the device after it has operated, to be avoided.

The device which I have herein shown for carrying out my invention, involves a spring, a swinging abutment adapted to detachably engage the spring and hold the same normally under restraint, a small quantity of heat susceptible material holding the abutment in position to hold the spring normally under restraint, and a heat concentrating device associated with the small quantity of heat susceptible material and adapted upon the passage of an unduly strong current in the protector, to soften such material and thereby permit the spring to shift the abutment sufficiently to permit its release and the opening of the circuit. In one form of such device herein shown, a plurality of movable abutments are provided and the spring is arranged for shifting movement so that it can engage any one of such abutments, and the abutments are included in a common circuit. By such arrangement, after one of the abutments has been shifted by the spring upon the softening of the heat susceptible material associated with such abutment, the spring can be immediately shifted so as to engage another abutment, whereby the circuit can be immediately put into use again without having to wait the repair or restoration of the first mentioned abutment to its normal condition. Any suitable number of shiftable abutments can be provided for operation in this way.

In the accompanying drawing. Figure 1

is a perspective view of a thermal protective device embodying a portion of my present invention; Fig. 2 is a plan view of a thermal protective device embodying a plurality of abutments; Fig. 3 is a vertical section of the same taken on line 3—3 in Fig. 2; Fig. 4 is a similar vertical section during the operation of the device; Fig. 5 is a detail of construction taken on line 5—5 in Fig. 2; Fig. 6 is a sectional view of another detail of construction.

In the device illustrated in Fig. 1, I have shown an insulating base 1 provided at one end with a spring 2 having a free end 3 which tends to rise or swing upwardly. At the other end of the insulating base 1 is a support 4 supporting and holding a metal rod 5. At the end of this metal rod 5 is a metallic clip 6 having an aperture through which the rod 5 extends, and having its lower surface made slightly concave, as shown in Fig. 6. The clip 6 is soldered to the metal rod 5 by a layer of solder 7 (Fig. 6). The free end of the spring 2 is provided with a graphite stick or rod 8 which extends under the clip 6 and rests in the concave lower surface thereof, whereby the clip 6 forms an abutment for holding the spring under restraint. The graphite stick 8 has such internal resistance and the solder 7 is capable of melting at such a comparatively low temperature, that an unduly strong current passing through the device will cause the stick 8 to generate sufficient heat to melt the layer of solder 7. The operation of the device therefore is as follows: During normal conditions, the spring 2 is held in restraint by the clip 6 at the end of the metal rod 5, so that the circuit is continuous from the spring 2 to the support 4 with whose bases the line is connected. When an unduly strong current traverses the circuit, the graphite stick 8 becomes sufficiently heated to melt the layer of solder 7 at the end of the rod 5, thereby loosening the spring and permitting it to swing the clip 6 upwardly and backwardly, in doing which it frees itself from the clip 6 and breaks the circuit.

The device shown in Figs. 2, 3, 4 and 5 comprises an insulating base 9 made in circular form as shown in Fig. 2. The base 9 is provided with a centrally located post 10 whose lower end is threaded and provided with nuts 11, 11, for connection with one of the line wires. Above the base 9 the post 10

is enlarged at 12 and is provided at its upper end with an adjusting screw 13. Between the head of this screw 13 and the top of the enlarged portion 12 of the post are located a spring 14, and a washer 15. A spring 16 is carried by the post 12, the spring having a flat portion 17 arranged between the washer 15 and the top of the enlarged portion 12 of the post, and the remaining portion of the spring being arranged in loop form so as to extend first upwardly and then downwardly. The lower end of the spring is provided with a piece of high resistance graphite 16^a. The spring has a tendency to move its free end outwardly, as shown in Fig. 4. The base 9 is provided with a circular metal plate 18, and around the outer edge of this plate are arranged a series of swinging lugs 19, 19, pivotally connected at their lower ends with the plate, as by means of a wire 20 extended around the periphery of the plate and inclosed in a hollow portion 21 formed thereon. These swinging lugs 19, 19, are each provided with a globule or small quantity 22 of solder capable of melting or softening at a comparatively low temperature, by which the lug 19 is soldered to the plate 18. As a preferred arrangement I place outside of each swinging lug 19 a small spring 23 tending to swing and hold the upper end of the block in an inward position. These springs 23, 23, are properly secured to the insulating base 9. The plate 18 is to be connected to the other side of the circuit as by a screw 24. The operation of this device is as follows: The spring 16 is primarily arranged so that its graphite stick or point 16^a is inside of the upper end of one of the swinging lugs 19, as shown in Fig. 3, whereby such lug forms an abutment for the graphite point or stick and holds the spring in restraint. So long as the conditions on the line are normal, the device remains in this condition, the circuit being properly closed between the lower end of the post 10 and the plate 18 by means of the spring 16, graphite point 16^a and swinging lug 19. When an unduly strong current traverses the line, however, the high resistance graphite 16^a is heated to such an extent as to melt or soften the readily fusible solder 22, whereupon the lug 19 is released by such solder and the spring 16 swings outwardly as shown in Fig. 4, thereby breaking the circuit between itself and the end of the plug. As soon as the spring 16 is freed from the lug 19 with which it was in engagement, the spring 23 applied to said plug automatically restores it to its vertical or normal position, this being done while the solder is still melted, by reason of the immediate action of the spring 23. A few minutes are required, however, for the solder to harden to enable the lug 19 to again withstand

strain of the spring 16. If it is desired to use the circuit immediately, the spring 16 is swung about its pivotal connection with the post 10 to one side or the other, and its graphite pencil 16^a placed in engagement inside of the upper end of another lug 19. The device remains in this condition until another unduly strong current traverses the line, when this second lug is released, thereby allowing the spring 16 to operate and open the circuit. After this has occurred, the spring 23 for such lug automatically restores it to its normal condition, but to secure continuity of the circuit immediately, the spring 16 can be swung so as to make contact with another lug 19, whereupon conditions remain as before until the device is separated by another unduly strong current. In this way the spring 16 can be caused to make connection successively with the various lugs or abutments 19, 19, of the device so as to allow immediate restoration of the circuit to its normal closed condition, and at the same time after each release of the spring 16, the abutment holding it is automatically restored to normal condition; thus the device can be used indefinitely in this way, without requiring any repair or replacement of parts.

In an application of mine filed of even date herewith Serial No. 104,021, I have set forth a somewhat different embodiment of the self-restoring springs 23, 23, and have claimed such self-restoring and self-soldering feature broadly. In the present application I shall simply claim its specific application to the present protector. In this application, however, I shall claim broadly certain features of construction involved in common in the device of this application, and of my said other application.

With reference to the two devices herein set forth, it will be noted that they have in common a spring held in restraint by a swinging abutment, which is in turn held in position by a small quantity of heat susceptible material associated with a heat concentrating device by which such material is softened or melted upon the passage of an unduly strong current. The two forms of device also have other features in common which will be noted in the claims.

It will be understood that I consider my present invention capable of much variation and modification, and hence do not desire to be limited to the specific structure herein shown and described.

What I claim as my invention is:—

1. In a thermal protective device, the combination with a circuit controlling device, of a plurality of devices co-operating therewith, means for connecting any one of the same in circuit, and means for restoring each of said devices to operative condition.

- abutments, of bodies or masses of heat susceptible material, one for each abutment, arranged to hold said abutments normally against movement, a circuit controlling device adapted to be placed in operative relationship with any one of said abutments and to be restrained thereby, means for affecting the heat susceptible material associated with the abutment coöperating with said circuit controlling device, and means for restoring each abutment to normal position, substantially as described. 5
3. The combination with a plurality of abutments, of bodies or masses of heat susceptible material, one for each abutment, arranged to hold said abutments normally against movement, a circuit controlling device adapted to be placed in operative relationship with any one of said abutments 10 and to be restrained thereby, means for affecting the heat susceptible material associated with the abutment coöperating with said circuit controlling device, and means for restoring each abutment to normal position after the same has been actuated so as to be swung and while said material is still affected, substantially as described. 15
4. The combination with circuit controlling mechanism, of a plurality of devices operable by an excess of current, each of said devices being adapted to coöperate with the circuit controlling mechanism and being adapted to be operated by the operation of the circuit controlling mechanism, and means for automatically restoring each of said excess operated devices. 20
5. The combination of a centrally mounted pivotally connected spring, a plurality of swinging abutments arranged in annular series, each of which is adapted to engage and restrain the free end of said spring, heat susceptible material holding said abutments in position to restrain the spring, springs for restoring said abutments to such position and means whereby the heat susceptible material for any abutment can be melted or softened upon the passage of an unduly strong current when the spring is restrained by such abutment. 25
6. The combination of a base provided with a centrally located post, a spring pivotally connected with said post so as to permit it to swing readily and having its free end provided with a graphite stick, a metal plate on the base provided with a plurality of pivotally supported abutments arranged in annular series, and small quantities of readily softenable solder for holding said abutments in normal position, substantially as described. 30
7. The combination of a base provided
- with a centrally located post, a spring pivotally connected with said post so as to permit it to swing readily and having its free end provided with a graphite stick, a metal plate on the base provided with a plurality of pivotally supported abutments arranged in annular series, small quantities of readily softenable solder for holding said abutments in normal position, and springs for automatically restoring the abutments to normal position, substantially as described. 65
8. An electrical circuit protector comprising a plurality of devices for controlling the circuit, adapted and arranged for use at different times, and having provisions whereby said devices automatically restore themselves to operative condition. 70
9. An electrical circuit protector, comprising a plurality of devices for controlling the circuit, adapted and arranged for use one after another, and having provisions whereby said devices are automatically resoldered in operative condition. 75
10. An electrical circuit protector comprising a plurality of solder-joint devices for opening the circuit, said devices being arranged for use at different times, and having provisions whereby said devices automatically resolder themselves after operation. 80
11. An electrical circuit protector, comprising a spring, a plurality of movable solder-secured devices for holding said spring in restraint, said devices being constructed to automatically resolder themselves in operative condition, and means for softening the solder of said devices to release them and permit operation of the spring. 85
12. An electrical circuit protector comprising a spring, a plurality of solder-secured devices each adapted to hold said spring in restraint, means whereby the solder joints of said devices can be softened to permit operation of said spring, and spring means for automatically returning said devices to their original positions after operation, whereby such devices are automatically reset and resoldered after operation. 90
13. A spring-actuated electrical circuit protector normally held in restraint by a device constructed to restore itself automatically after operation to condition to hold the protector again in restraint, and having a plurality of such devices adapted and arranged for use one after another. 105

In witness whereof, I hereunto subscribe my name this 7th day of April A. D., 1902.
